Specification for Design.

Patented May 25, 1920.

Application filed November 25, 1919. Serial No. 340,687. Term of patent 7 years.

To all whom it may concern:

Be it known that I, JOHN C. ROBERTSON, a subject of the King of Great Britain, residing at Glasgow, Scotland, have invented a new original, and ornamental Design for Golf-Balls, of which the following is a specification, reference being had to the accompanying drawing, forming part thereof.

In the drawing accompanying,—

Figure 1 is a pole, or plan, view of a golf ball embodying my design.

Fig. 2 is an equatorial, or side elevation, taken at right angles to the view shown in Fig. 1.

I claim:

The ornamental design for a golf ball as shown.
